UNITED STATES PATENT OFFICE.

HENRY ALFRED GSELL, OF PARIS, FRANCE.

MATCH-MAKING MACHINE.

1,054,764.

Specification of Letters Patent.

Patented Mar. 4, 1913.

Application filed September 9, 1911. Serial No. 648,511.

To all whom it may concern:

Be it known that I, HENRY ALFRED GSELL, a citizen of the Swiss Confederation, residing at Paris, France, have invented new and useful Improvements in Match-Making Machines; and I do hereby declare the following to be a full, clear, and exact description of the same.

My present invention relates to a match-making machine of the kind described in my prior United States Patent, No. 1,020,644, issued March 19, 1912, and wherein in two or more reciprocating slides are used for inserting splints or sticks into the per-
10 forated dipping bars, said slides being normally in line behind each other and moved one above the other during the forward stroke, for the purpose of simultaneously inserting a plurality of rows of splints in the 15 dipping bars.

The object of my present invention is to provide a machine of this kind, wherein a plurality of rows of splints is inserted at the forward stroke and also a plurality of rows 25 of splints at the backward stroke of the devices. This result is attained by the use of two pairs of slides, one pair of slides serving to insert splints at the forward stroke, while the second pair of slides serves to 30 insert splints at the backward stroke, the splints being delivered from a single hopper.

My invention will be readily understood from the following description taken in connection with the accompanying drawings, wherein—

Figure 1 is a vertical longitudinal section through the hopper and slides, showing the guide pulleys over which is guided the chain 40 of dipping-bars. Fig. 2 is a vertical cross section through the hopper and the upper slide along the center lines of the hopper. Fig. 3 is a front view of the slides superposed one above each other during the splint 45 inserting operation, the slides showing grooves of different depths, the dipping bars showing the respective scheme of the perforations. Fig. 4 is a front view of the slides superposed one above each other during the 50 splint inserting operation, the slides showing grooves of equal depths, the dipping bars showing the respective scheme of the perforations. Fig. 5 is a side view of the 55 raising mechanism for the two tongued upper cross-bars and the vertically movable

guide-way for the tongued lower cross-bars, the hopper being suppressed.

Arranged below the usual hopper 1 is a reciprocating carriage 2 being actuated by two lateral levers 35 connected to an eccentric tappet and carrying at opposite sides grooved slides 3, 4 between which is arranged a plate 5 having a smooth upper surface overtopping the surface of the slides 3, 4 by the thickness of one splint. The 60 grooves of the slides 3, 4 may be made of equal depths or of different depths, according as it is desired to insert one or two rows of splints by each slide at each operation (see Figs. 3 and 4). The grooves of these 65 slides are open on both ends, however the inner ends thereof may be temporarily closed by tongued cross-bars 6 and 7 respectively, movable and guided vertically and provided at their upper ends with rollers 8, adapted to roll on stationary guide-ways 9, 10 and vertically movable guide-way 11. The latter is secured to or made integral with two tongued cross-bars 13, 14 70 movably arranged on opposite sides of the 75 hopper 1 respectively on its guide bars 12 and guided by sliding block 34 and connecting piece 15. Sliding block 34 provided with a pivoting arm 16, connected to a suitable driving part (cam or the like) of the 80 machine, whereby said cross-bars 13, 14 and guide-way 11 are raised and lowered to 85 about the thickness of a match at suitable intervals hereinafter referred to.

Fig. 5 shows the sliding block 34 to which 90 are connected the tongued cross-bars 13, 14 and guide-way 11. In the spaces 36 left open the ends of the horizontally movable guide bars 12 of the hopper 1 are reciprocated, the spaces 36 allowing the sliding 95 block 34 to be vertically lowered and raised about a few millimeters.

The carriage 2 carries horizontal bolts 17, 18 serving to guide the supports 19, 20 of the vertically and horizontally movable 100 slides 21, 22, which are also provided with grooves of equal or different depths. The supports of these slides are provided with rollers 23, 24 adapted to roll on rails having an upper central horizontal position 25 and 105 two opposite lower horizontal portions 26, 27 these horizontal portions being connected by inclines 28, 29. The grooves of the slides 21, 22 are open on both ends, the front sides of the slides 3, 4 serving as rest for the 110

splints in the slides 21, 22, when passing below the hopper 1, while at the moment of the inserting operation the front sides of the cross-bars 6, 7 serving as rest for the splints in the slides 21, 22.

5 The endless chain formed of the splint-bars 33 passes over the guide pulleys 31, 32 arranged at opposite sides of the hopper 1, the carriage 2 with the slides 3, 4, 21, 22, being reciprocated between the pulleys 31, 32.

10 The operation is as follows: The parts being in the positions shown in Fig. 1, the pairs of slides 3, 21 are superposed and about to insert splints in the splint-bars at 15 A (Fig. 1), while the slides 4, 22 of the second pair are arranged in line behind each other, the slide 22 being just below the hopper 1 to receive splints in its grooves.

The carriage 2 being now moved to the 20 right, the slide 22 filled with splints, will be pushed to the right by the slide 4, and when the latter comes below the hopper splints will also be delivered into its grooves. At this moment the tongued cross-bars 13, 14 25 and guide-way 11, will be raised to the thickness of a splint, whereby the rear end of the grooves of the slide 4 will be closed by the tongued cross-plate 7, the tongued cross-bars 13, 14 being then in position to 30 prevent the feeding of more than one splint from each groove of said slide 4. The movement to the right being continued, the rollers 8 of the cross-plates 6, 7 will come upon the stationary guide-way 10, whereby said 35 plate is held in its raised position for the insertion of the splints in the splint-bars at B (Fig. 1). During the movement to the right, the rollers 24 roll downwardly along the incline 29 whereby the slide 22 is lowered 40 below the slide 4. At the end of the stroke to the right, the two slides 4, 22 are just above each other for the insertion of splints at B as shown by the dotted lines, which represent the position of the inserting apparatus with its two slides, 4, 22 in position 45 at B in Fig. 1. In the meantime the tongued cross-bars 13, 14 and guide-way 11, have been lowered again to the thickness of one splint.

50 At the beginning of the movement to the right the slide 3 is moved to the right while the slide 21 remains in its position until the stop of the bolt 17 strikes against its abutment, whereupon the slide 21 is also moved 55 to the right and raised in line with the slide 3, as its roller 23 rolls upwardly along the incline 28. The roller 8 of the cross-plate 6 coming upon the lowered guide-way 11, said cross-plate will be lowered, and the 60 slides 3, 21 pass successively below the hopper 1, until the slide 21 is brought below the hopper to be filled with splints. Now the carriage 2 is moved to the left, and as soon as the slide 3 is brought below the hopper, 65 the cross-plate 6 and guide-way 11, will

be raised as before and the slide 21 lowered again when the roller 8 of the cross-plate 6 has reached the stationary guide-way 9. During the movement of the carriage 2 to the left, the slides 3, 21 are brought above 70 each other as already described for the insertion of splints at A.

It will be seen from the foregoing description that a plurality of rows of splints are inserted at the stroke to the right as well as 75 at the stroke to the left, the splints being delivered from a single hopper. The parts are arranged in such manner that the rows of perforations into which no splints are inserted at A, receive splints at B from the 80 slides 4, 22. After the splint bars are moved around the pulley 32, all the perforations thereof are filled with splints.

I wish it to be understood that vertically movable slides 21, 22 may be omitted in 85 the arrangement described without departing from the scope of the invention.

Having fully described my invention, what I claim and desire to secure by Letters Patent is:

90 1. In a match-making machine, the combination with a hopper for delivering splints, guide-pulleys on opposite sides of said hopper, and a chain of perforated dipping bars passing over said guide-pulleys, a carriage reciprocated between said pulleys and below the hopper, and a grooved slide at opposite sides of said carriage, so that splints are inserted in the perforated dipping bars on each guide-pulley, substantially as set forth.

95 2. In a match-making machine, the combination with a hopper for delivering splints, guide-pulleys on opposite sides of said hopper, and a chain of perforated dipping bars 100 passing over said guide-pulleys, a carriage reciprocated between said pulleys and below the hopper, grooved slides secured to opposite sides of said carriage, vertically movable cross-plates, adapted to temporarily 105 close the inner ends of the grooves of said slides, and means for raising and lowering said cross-plates at certain intervals, substantially as set forth.

110 3. In a match-making machine, the combination with a hopper for delivering splints, guide-pulleys on opposite sides of said hopper, and a chain of perforated dipping bars passing over said guide-pulleys, a carriage reciprocated between said pulleys 115 and below the hopper, grooved slides secured to opposite sides of said carriage, vertically movable tongued cross-plates, adapted to temporarily close the inner ends of the grooves of said slides, rollers at the upper ends of said cross-plates, stationary horizontal guide-ways at opposite sides of the hopper and above the carriage, whereon said rollers are guided, vertically movable guide-way between said stationary guide-ways and 120

125

130

adjacent to the hopper, vertically movable tongued cross-bars on opposite sides of the latter and attached to said movable guide-way, and a suitable mechanism for raising and lowering said cross-bars at certain intervals, substantially as set forth.

4. In a match-making machine, the combination with a hopper for delivering splints, guide-pulleys on opposite sides of said hopper, and a chain of perforated dipping bars passing over said guide-pulleys, a carriage reciprocated between said pulleys and below the hopper, grooved slides secured to opposite sides of said carriage, ver-

tically movable cross-plate at the inner ends 15 of the grooves of said slides, vertically and horizontally movable slides, normally in line with the slides secured to the carriage, and means for lowering said movable slides below the former for inserting splints in 20 the dipping bars, substantially as set forth.

In testimony whereof, I have signed my name to this specification in the presence of two subscribing witnesses.

HENRY ALFRED GSELL.
